UNITED STATES PATENT OFFICE.

DANIEL PENMAN AND E. FITZGERALD, OF NEW YORK, N. Y., ASSIGNEES TO WM. C. WALKER AND M. PENMAN, OF SAME PLACE.

MACHINE FOR MANUFACTURING RUCHES.

Specification of Letters Patent No. 26,328, dated November 29, 1859.

To all whom it may concern:

Be it known that we, DANIEL PENMAN and ELISHA FITZGERALD, of the city, county, and State of New York, have invented a new and Improved Construction of Machines for Forming and Making Ruches Used in Millinery; and we hereby declare that the following is a full and exact description thereof.

10 To enable others to make and use our invention we proceed to describe its construction and operation, reference being had to the drawings hereunto annexed and making part of this specification.

15 Figure 1 is a bird's eye view; Fig. 2, vertical section from end to end; Fig. 3, elevation of the end.

The same letters refer to the same things in all the drafts.

20 A is the pressing bar; B, crank; C, pins upon the arms of the pressing blade; D, the hook rods or straps; E, guide straps to govern the movement of the rods D; F, levers on the shaft G; G, shaft of the treadle;

25 H, treadle, by which the pressing bar or blade is brought down; I, the gage bar, against which the ruch is placed to be pressed; J, the hook which catches upon the pin, C, on the arm of the pressing bar; K, 30 a weight to balance the pressing bar; L, shaft on which are set the arms of the pressing bar, A, and having a crank on its end.

When a ruch has been prepared and gathered, there is a starched thread put in it and 35 it is pressed with a hot metal bar to set it. To press and form permanently the ruch this machine is constructed.

The frame should be of the proper height for an operative to work at standing, or sitting on a high stool. The machine should be made double, as in the drawing, for economy as the bars, A, are thrown back and meet in the center to be heated, and the two can be heated at the same time as easily 45 as one. The ruch, when ready for the ma-

chine, is laid upon the top with its back against the gage bar. The operative, by means of the crank brings over the pressing bar, when by pressure of the foot upon the treadle the notch, J, catches on the pin, C, 50 and the bar A, is brought down with the requisite force.

One of the novelties in this machine is the apparatus connected with the pedal, by which the rod, D, can catch and pull down 55 the pressing bar. It cannot be done well by the crank, in this construction of machines, as it is laborious and produces an unequal pressure.

The hook rods, D, are held at the upper 60 ends by the straps, E. When the pedal is up the hook rods are thrown toward the operator by the hinged straps, E. When the treadle is pressed down the hinged strap, E, thrusts the hook-rod from the operator and 65 it catches the pin, C, and the pressing blade, A, is brought down and held upon the ruch. The length of the lever, F upon the pedal shaft may be varied so as to give more or less power to the foot, and the guide straps 70 E, may be varied in length and in position and still operate effectively. The gage can be moved and adjusted by the screws moving in a slot in the top of the frame.

What we claim as our invention and desire to secure by Letters Patent is—

The pressing bar A, attached to the shaft L, by the arms M, (said shaft having a crank, B, at its end for the purposes described) in combination with the adjustable 80 gage bar, I, hook rods, D, and treadles, H, the whole being constructed and operated substantially in the manner and for the purposes set forth.

DANIEL PENMAN.
ELISHA FITZGERALD.
